UNITED STATES PATENT OFFICE.

HENRIK HILLBOM, OF WALLINGFORD, CONNECTICUT, ASSIGNOR TO R. WALLACE & SONS MFG. CO., OF WALLINGFORD, CONNECTICUT, A CORPORATION.

DESIGN FOR A HANDLE FOR SPOONS, FORKS, OR SIMILAR ARTICLES.

No. 38,784.

Specification for Design.

Patented Sept. 3, 1907.

Application filed July 25, 1907. Serial No. 385,592. Term of patent 7 years.

To all whom it may concern:

Be it known that I, HENRIK HILLBOM, a citizen of the United States, residing at Wallingford, in the county of New Haven and State of Connecticut, have invented a new, original, and useful ornamental Design for a Handle for a Spoon, Fork, or Similar Article; and I do hereby declare the accompanying drawings to be a full, clear, and exact illustration of the same, and which said drawings

constitute part of this specification and represent a face view of a handle for a spoon, fork, or similar article.

Claim:

The ornamental design for a handle for a spoon, fork or similar article as shown.

HENRIK HILLBOM.
